BELGIAN AMERICAN COKE OVENS CORPORATION, OF WILMINGTON, DELAWARE,
A CORPORATION OF DELAWARE.

COKE-OVEN WALL.

Application filed November 6, 1918. Serial No. 261,421.

(GRANTED UNDER THE PROVISIONS OF THE ACT OF MARCH 3, 1921, 41 STAT. L., 1313.)

To all whom it may concern:

Be it known that I, OLIVIER PIETTE, a subject of the King of the Belgians, and a resident of Brussels, Belgium, have invented 5 certain new and useful Improvements in Coke-Oven Walls (for which I have filed application for patent in France October 22, 1917, Patent No. 487280), of which the following is a specification.

10 In coke ovens as generally constructed, the flue walls or piedroits are built up of solid headers and stretchers, the headers being spaced from each other to form the flues through which heating gases pass. The stretchers, which in this well known construction are simply placed one upon the other, have to be made of considerable thickness in order to enable them to resist the strain caused by the mechanical emptying 15 and cleaning of the oven; this thickness is usually from twelve to fourteen centimeters at the bottom of the piedroit, and about ten centimeters toward the top. The objection to stretchers of such thickness is that they transmit heat but poorly and slowly from the heating channels or flues to the coking chambers, thereby reducing the efficiency 20 and the output of the oven.

25 By the novel construction described and claimed hereinafter, I avoid these drawbacks and obtain a strong flue wall or piedroit in which the heat-transmitting portions are relatively thin so that heat will be transmitted readily from the flues to the coking chambers, with a resulting increase in output and efficiency.

30 In the accompanying drawings Figs. 1 and 2 are similar horizontal sections showing two different constructions of flue walls or piedroits embodying my present invention, Figs. 3 and 4 are perspective views, respectively, of the bricks and header bricks shown in Fig. 1, and Fig. 5 is a similar view showing the bricks of Fig. 2.

35 In Fig. 1 the bricks 1, 2 of the piedroit are alike. Each of these bricks is hollow so as to form a channel or flue α , and is provided, at the exposed face, with unsymmetrical projections b and c respectively. The 40 relatively long projections c are of such length as to come in contact with those of adjoining bricks, while the short projec-

tions b of adjoining bricks do not come into mutual contact. The side surfaces of the bricks are concave, and between them are fitted header bricks 3 having corresponding convex side surfaces. It will be seen that the bricks 1, 2 and 3 extend from one exposed face of the flue wall to within a distance from the other exposed face. One of these exposed faces is formed by the bricks 1, 3, and the other by the bricks 2, 3. Each brick 1, 2, has a transverse inner member 4, these members forming a partition between adjacent flues α . The bricks 1 are placed alternately in different positions, as shown, and the bricks 2, likewise, so that two bricks 1 or 2 which are in contact with each other by their long projections c will be out of contact with the adjoining bricks, there being a regular alternation of contacting projections c and non-contacting projections b . In the illustrated example, the separated relation of the non-contacting short projections b is maintained by means 75 of the header bricks 3; obviously, the latter may be replaced by other means whereby an equivalent result is obtained if, for any reason, this is desirable. The walls of these hollow bricks 1, 2, are relatively thin, particularly at their exposed faces where they form the surface of the coking chamber; this thickness will be say only one-half of the thickness employed hitherto, and the heating effect will be increased accordingly. Yet 80 a piedroit or flue wall so constructed is very strong and stable.

The same advantages are secured when using the construction shown in Fig. 2. Here the two sets of bricks 1', 2', instead of being alike, are of different thickness or depth, and are used alternately, that is to say, each exposed surface of the flue wall or piedroit is composed of bricks 1' extending less than half-way into the wall, alternating 95 with bricks 2' extending more than half-way into the wall. The bricks 1', 2', are hollow to form the channels or flues α' for the heating gases. Each brick is provided with a lateral projection b' at one side, at the outer or exposed wall portion, and with another projection c' at the other side, at the inner portion lying within the wall. All bricks 1' are alike, and all bricks 2' are alike, but

they are used in different positions at opposite faces of the flue wall or piedroit. The projections b' , c' , of the bricks interlock as shown, and a very strong construction is thus obtained. Unbroken exposed surfaces are obtained with this construction without using any additional bricks such as 3 in Fig. 1.

In each construction the end bricks may 10 be given a special shape, but the main portion of the flue wall consists of bricks of the character described.

Various modifications may be made without departing from the nature of my invention 15 as set forth in the appended claims:

I claim:

1. A flue wall comprising hollow bricks forming flues, each of said bricks having a lateral projection at each side of one of its 20 faces, the projection at one side of each brick extending a greater distance therefrom than the projection at its other side, the larger projections of two adjacent bricks contacting with each other, and the smaller 25 projections of two adjacent bricks extending toward each other but being separated and means for maintaining said separated relation of said smaller projections.

2. A flue wall comprising hollow bricks 30 forming flues, each of said bricks having a lateral projection at each side of one of its faces, the projection at one side of each brick extending a greater distance therefrom than the projection at its other side, 35 the larger projections of two adjacent bricks contacting with each other while the smaller projections of two adjacent bricks extend toward each other but have a separation therebetween, and a filler brick interposed

between the two adjacent hollow bricks and 40 extending into said separation.

3. A flue wall comprising hollow bricks forming flues, each of said bricks having concave lateral surfaces and a lateral projection at each side of the brick, the projection at 45 one side of each brick extending a greater distance therefrom than the projection at its other side, the larger projections of two adjacent bricks contacting with each other while the smaller projections of two adjacent 50 bricks extend toward each other but have a separation therebetween, and a filler brick having convex sides adapted to fit the concave lateral surfaces of two adjacent hollow bricks and provided with an extension 55 for filling the separation between the smaller projections thereof.

4. In a flue wall, two rows of hollow bricks forming flues, each brick having two unbroken surfaces and two surfaces provided with lateral projections, the projection of a brick in one row being adjacent to the projection of an adjacent brick in the same row, one unbroken surface of each brick in the two rows forming a part of 60 the exterior of the flue wall, and the other unbroken surface of a brick in one row contacting with the other unbroken surface of a brick in the other row, and means for maintaining said projections in each adjacent 65 relation.

In witness whereof I have signed this specification in the presence of two witnesses.

OLIVIER PIETTE.
